[57] CLAIM

The ornamental design for a pharmaceutical tablet, substantially as shown.

DESCRIPTION

FIG. 1 is a front view of a pharmaceutical tablet illustrating our new design;

FIG. 2 is a right side view thereof as shown in FIG. 1; FIG. 3 is a left side view thereof as shown in FIG. 1;

FIG. 4 is a back view thereof as shown in FIG. 1;

FIG. 5 is a top view thereof as shown in FIG. 1;

FIG. 6 is a bottom view thereof as shown in FIG. 1; and

FIG. 7 is a cross-sectional view thereof taken through line 7—7 of FIG. 1.
